UNITED STATES PATENT OFFICE.

JOSEPH J. WELTE, OF ST. PAUL, MINNESOTA, ASSIGNOR TO HERMAN SCHOENER, OF ST. CLOUD, MINNESOTA.

ROLL WRITING TABLET.

Application filed November 24, 1920. Serial No. 426,226.

To all whom it may concern:

Be it known that I, JOSEPH J. WELTE, a citizen of the United States, residing at St. Paul, in the county of Ramsey and State of Minnesota, have invented a new and useful Roll Writing Tablet, of which the following is a specification.

This invention relates to writing tablets of the continuous web type, it being the primary object of the invention to provide a tablet wherein portions thereof which have been used, may be rolled out of sight of the operator, the portion being capable of being unwound into full view, for copying purposes.

A further object of the invention is to provide a device of this character wherein the rolls may be readily and easily removed from the frame, and replaced, when a roll becomes filled.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:—

Figure 1 illustrates a plan view of a tablet constructed in accordance with the present invention.

Figure 2 illustrates a side elevational view of the same; and

Figure 3 illustrates a sectional view taken on line 3—3 of Figure 1.

Figure 4 is a transverse sectional view through the device taken substantially intermediate the ends thereof.

Referring to the drawing in detail, the device is shown as comprising a frame which is made up of a pair of side bars 5 and end bars 6, formed preferably of flexible sheet metal, the side and end bars being connected at the adjacent end portions thereof.

The side bars 5 are tapered towards the forward ends thereof, so that the frame will be supported at an angle with respect to the lower edges of side bars 5 to facilitate the use of the device.

Secured to the side bars 5 and one of the end bars adjacent to the upper edges thereof,

is a table portion 7 which has the surface thereof ruled with transversely extending lines indicated at 8, which lines are of a character to be clearly visible through the web indicated at 9, and which operates in close proximity to the table 7.

A pair of rolls indicated at 10 and 11 are disposed in spaced relation with each other, and supported adjacent to the upper extremity of the frame as by means of the spring clips 12, each of which includes a length of spring material having its ends curved upwardly as indicated at 13, the central portion or portion intermediate the ends of the respective clips being secured to the side bar associated therewith, as by means of the securing bolts 14.

From the foregoing it is obvious that by lifting the ends of the spring clips 12, the rolls supported thereunder may be readily and easily removed in the event that it becomes necessary to replace a roll.

Each roll is provided with a shaft 15 which is provided with a circumferential groove designed to accomodate the spring 80 clips for restricting lateral movement of the rolls with respect to the frame.

One of these rolls is a delivering roll and the other roll is a receiving roll, that is, the web 9 which is wound on one roll, 85 has its free end secured to the opposed roll, so that rotary movement of one roll will cause the web 9 to be moved over the table 7.

Secured to the side bars 5 as by means 90 of the rivets 5' is a plate 16 over which the web 9 operates, the web passing over the table 7, where the same may be written on.

In order that the web 9 will not be torn during the operation of the device, the table 95 7 is provided with downwardly and inwardly extending portions 17 forming guides for the web to guide the same over the table.

In the operation of the device, the web 100 which is wound on one of the rolls, is wound on the opposite roll by rotating the same. It is of course obvious that as the portion of the web, which is resting on the table 7, is used, that portion is wound on 105 the receiving roll, and when the web has been completely filled, the roll may be filed away.

It might be further stated that due to this construction, any portion of the web 110

may be readily referred to, by simply rotating the opposed roll, whereupon the web is moved to bring portions thereof to view.

Having thus described the invention, what is claimed as new is:

In a writing tablet, a frame including side and end bars, a plate having right angled ends supported between the side bars and having connection therewith, means extending through the right angled ends and side bars for securing the plate in position, a table secured to the side bars adjacent to the upper edges thereof, said table being of a length to provide a space

between one end thereof and one end bar 15 of the frame, the table having curved upper and lower edges, spring clips secured to the side bars, rolls supported under the spring clip, said frame and rolls adapted to support a web and means for operating the 20 rolls.

In testimony that I claim the foregoing as my own, I have hereto affixed my signature in the presence of two witnesses.

JOSEPH J. WELTE.
